UNITED STATES PATENT OFFICE.

NICHOLAS ALBERTI, OF CHICAGO, ILLINOIS.

WOOD WIND INSTRUMENT.

1,103,555.

Specification of Letters Patent.

Patented July 14, 1914.

Original application filed August 5, 1911, Serial No. 642,447. Divided and this application filed March 1, 1913. Serial No. 751,444.

To all whom it may concern:

Be it known that I, NICHOLAS ALBERTI, a citizen of the United States, and a resident of Chicago, in the county of Cook and State 5 of Illinois, have invented an Improvement in Wood Wind Instruments, of which the following is a specification.

My invention relates to improvements in musical instruments, and it consists in the 10 combinations, constructions, and arrangements herein described and claimed.

An object of my invention is to provide means for tuning wind instruments, such as flutes, clarinets and the like.

15 A further object of my invention is to provide means for simultaneously changing the pitch of the notes produced by the opening of the different valves.

A further object of my invention is to 20 provide a device which is comparatively simple in its construction for accomplishing the first-named objects, and which is not liable to get out of order.

Other objects and advantages will appear 25 in the following specification, and the novel features of the invention will be particularly pointed out in the appended claims.

30 My invention is illustrated in the accompanying drawings forming part of this application in which—

Figure 1 is a plan view of the device, Fig. 2 is a plan view of the inner tube, the end piece being removed and Fig. 3 is a detail view showing the relative positions of the 35 openings in the sleeve and the inner tube.

In explanation of the purpose of the device, I may say that there is in use in this country and in others what is known as "concert pitch" and "international pitch," 40 the latter being approximately one-half tone lower than the former. Many times musicians are obliged to make use of both of these pitches, or they are compelled to transpose the music, which is a very difficult 45 thing to do, and can only be done after one becomes an expert. It is customary with some musicians to have instruments of different pitch, but this is expensive and necessitates the carrying of an extra instrument.

50 My purpose as stated above, is to provide a device which may be quickly changed by a semitone.

This application is a division of a prior application, #642,447, filed August 5, 1911.

55 Referring now to Fig. 2 I have shown a

mouth piece A' secured to the end member A^y of an inner tube or sounding pipe B'. The latter is provided with a series of openings b³, the distance between these openings representing a half tone. Near the end member A^y the tube B' is provided with four small openings b⁴, the distance between these openings also corresponding to a half tone.

A sleeve D' is provided with openings d² which are made progressively longer from 65 the end nearest the mouth piece to the opposite end and which are arranged to register with the openings b³ in the tube or sounding pipe B' when the parts are in the position shown in Fig. 1. On the opposite 70 end of the tube B' from the end member A^y is secured an end member C' as shown in Fig. 3. The tube B' is provided with a longitudinal guide slot b' in which a guide pin d' carried by the sleeve D' projects to guide 75 the sleeve in its movement on the tube. The openings d² in the sleeve D' are covered by valves V which are arranged to be operated in any suitable manner. In the drawing I have shown only part of these valves, but 80 it will be understood that each of the openings d² in the sleeve D' is to be covered by a valve. Two smaller valves V' are intended to cover the four small openings b⁴ in the tube B' as will be hereinafter explained. It 85 will be noted that there is only one set of valves for this instrument, and that this one set of valves serves for operating the instrument in either pitch.

From the foregoing description of the 90 various parts of the device the operation thereof may be readily understood.

If it is desired to vary the pitch by half a tone the sleeve D' is moved relatively to the tube or pipe B' so that the openings in the 95 sleeve D' now register with the openings adjacent to those with which they formerly registered. This will result in the changing of the pitch of all of the notes of the instrument half a tone. The first and second 100 small valves V (counting from the left end of Fig. 1) will cover the first and third small holes b⁴ respectively, in the normal position of the sleeve D'. In the shifted position of the sleeve D' these valves will 105 cover the second and fourth openings respectively.

It will be apparent that only one set of valves is necessary since all of the valves are shifted simultaneously. The mechanism 110

is simple and is not likely to get out of order like those instruments in which one set of valves are put into or out of commission and a new set of valves is used.

9 While I have shown my invention as applied to a flute, it will be obvious that it is equally applicable to a reed instrument such as a clarinet in which the different tones are produced by covering or uncovering openings in the sounding pipe. I therefore do not consider the invention limited to a flute, but consider it is applicable to any device in which the tones are produced by uncovering and covering the openings in the sounding pipe.

15 I claim:

1. In a wood wind instrument, a sounding pipe provided with a single set of openings, the distance between the openings corresponding to a semitone, a sleeve mounted on said sounding pipe and having a single set of valve openings arranged to register with some of the openings in said pipe, a single set of valves arranged to close the 20 valve openings in said sleeve, said sleeve being movable longitudinally of said pipe, the movement of said sleeve serving to bring each valve into registration with the opening in the pipe adjacent to that with which 25 it first registered.

2. In a wood wind instrument, a sounding pipe provided with a single set of openings, the distance between the openings corresponding to a semitone, a sleeve mounted 30 on said sounding pipe and having a single set of valve openings arranged to register with some of the openings in said pipe, a single set of valves arranged to close the valve-openings in said sleeve, said sleeve being 35 movable longitudinally of said pipe, the movement of said sleeve serving to bring each valve into registration with the opening in the pipe adjacent to that with which 40 it first registered.

it first registered, and means for guiding the sleeve in its movement, said means comprising a pin carried by the sleeve and arranged to extend in a slot in the pipe. 45

3. In a wood wind instrument, a sounding pipe provided with a single set of openings, the distance between the openings corresponding to a semitone, a sleeve mounted on said pipe and having a single set of valve openings arranged to register with some of the openings in said pipe, a single set of valves or keys arranged to close the valve 50 openings in said sleeve, said sleeve being movable on said pipe in a longitudinal direction, the movement of said sleeve serving to vary the registration of all the openings in the sleeve with the openings in the 55 said pipe so that when the sleeve is moved toward the mouth piece its valve openings will register with openings of the said pipe that will be a half tone higher than when the said sleeve is moved and set in its position away from the mouth piece. 60

4. In a wood wind instrument, a sounding pipe provided with a single set of openings, the distance between said openings being progressively greater from one end of the 70 pipe to the other, said distance between the openings corresponding to a semitone, a sleeve mounted on said sounding pipe and having a single set of openings of progressively greater length and arranged to register with some of the openings in said pipe, a single set of valves to close the openings in said sleeve, said sleeve being movable longitudinally of said pipe, to bring each valve 75 into registration with the opening adjacent 80 to that with which it is registered. 80
